United States Patent Office.

SEBEUS C. MAINE, OF BOSTON, MASSACHUSETTS.

Letters Patent No. 63,065, dated March 19, 1867.

IMPROVED WARDROBE BEDSTEAD.

The Schedule referred to in these Letters Patent and making part of the same.

TO ALL WHOM IT MAY CONCERN:

Be it known that I, SEBEUS C. MAINE, of Boston, in the county Suffolk, and State of Massachusetts, have invented an improved Balanced Bed and Bedstead, of which the following is a full, clear, and exact description, reference being had to the accompanying drawings making part of this specification, in which—

Figure 1 is a perspective view of my improved bedstead as it appears when closed and standing in the parlor or place where it is intended to be used.

Figure 2 is a view of the bedstead and bed when the bedstead is opened and the bed exposed and ready for use.

Figure 3 is the balance-spring.

The class of bedsteads most in use are objectionable because of the amount of room required and the exposure of the bed and bedding to view, while other classes of bedsteads are still more objectionable, for while they obviate in a great measure the first objection, viz, the space required and the exposure of the bed and bedding during the day, still, when used, the room required for the case or shell when removed, the wearing of carpets, the noise and labor of getting the bed ready for use, and in many cases the exceeding high cost, putting them beyond the means of the common people, are great objections to their use. My invention has for its object to remove the above-mentioned difficulties, and to give to all a bedstead requiring the least possible space, to be operated without noise or labor, and at a price within the means of all, and consists in an upright case or frame resembling any article of furniture desired, a book-case, wardrobe, or sideboard. The front may be plain, panelled, or it may contain a mirror, as the one herein described. The front or face of the piece of furniture selected for a bedstead becomes, when used as a bedstead, the bottom of an inner case which contains the bed and bedding. The inner case or frame which contains the bed is secured by bolts or screws to a shaft crossing the frame at any desired distance from the bottom, the shaft turning on proper bearings at each end. Under this shaft, upon the bottom of the frame, and parallel with the shaft, is a flat spring secured to the bottom in the centre, and attached to the shaft with chains or any suitable cord or strap from the ends of the spring, (coiled or wound springs can be used,) attached to the back or side of the outer case or frame. When a spring of proper strength is thus applied, the bed in the inner case can be dropped or swung out from the frame without noise, and requiring but little strength, as the increased weight of the inner case and bed is balanced by the increased power of the spring. When the inner case has been lowered to a level with the bearing of the shaft, two pieces of the finish of the inner case drop with their own weight and become legs or supports for the bottom of the bedstead. The only labor required in closing this bedstead is to put the hand under it and give it a gentle motion upward, when, with the assistance of the spring, the whole is at once transformed to its former shape.

To enable others skilled in the art to understand and use my invention, I will now proceed to describe the manner in which I have carried it out. In the said drawings—

Figure 1 is a case provided with a mirror in the front and commode under the mirror, with a top or cover that may be elevated to a level and used as a shelf or toilet-table, the whole making a neat and useful piece of furniture.

Figure 2 represents the outer frame as seen in fig. 1, also the inner frame *a*, which contains the bed, while *a* is the spring attached to the bottom of the frame, *b* the shaft to which the frame containing the bed is secured, and *c* the chain connecting the ends of the spring to the shaft; *g* is the cap which holds the spring in its place; *e* is a section of the ornamental finish on the front of the case as it appears when closed, while *f* represents another section of the same finish dropped by its own weight and forming legs for the inner frame.

Operation.

If it is desired to convert this piece of furniture into a bedstead and bed, take hold of the frame of the mirror, fig. 1, and pull it gently from the top of the frame; the weight of the inner frame and bed will give it motion, while the motion will be controlled and regulated by the spring. When the inner case with the bed has been dropped to a line at right angles with the outer case or frame, the weight of the inner case and bed becomes greatest, acting as a lever upon the shaft; at the same time the power of the spring is greatest and acting also upon the shaft. The same balancing power may be seen in closing; as the bed advances towards the case the weight becomes less until it stands erect in the frame, when a pound's weight will hold it in its place. So, too, with the spring, for when the bed stands erect the spring also is at rest.

What I claim as my invention, and desire to secure by Letters Patent, as an improved bedstead and bed, is—

The balance-spring *a*, or its equivalent attached to shaft *b* by chains or their equivalent, in combination with frames or cases as shown in figs. 1 and 2, and operated substantially as set forth.

S. C. MAINE.
